CLAIM

The ornamental design for a plastic sheet with a surface pattern, as shown and described.

DESCRIPTION

FIG. 1 is a top view of a plastic sheet with a surface pattern; and,

FIG. 2 is an enlarged view of the plastic sheet with a surface pattern shown circumscribed within FIG. 1.

(Continued)

The broken line surrounding FIG. 1 and the area outside the inner broken line depict portions of the plastic sheet with a surface pattern that form no part of the claimed design. In FIG. 2, the broken line perimeter is the boundary to the claim and forms no part thereof. The inner broken line and the area and features within it depict portions of the plastic sheet with surface pattern that form no part of the claimed design.
